WILLIAM J. ROGERS, OF SEATTLE, WASHINGTON.

DIVING APPARATUS.

1,139,805.

Specification of Letters Patent. Patented May 18, 1915.

Application filed April 2, 1914. Serial No. 829,007.

To all whom it may concern:

Be it known that I, WILLIAM J. ROGERS, a citizen of the United States, residing at Seattle, in the county of King and State of Washington, have invented certain new and useful Improvements in Diving Apparatus, of which the following is a specification:

This invention relates to diving apparatus for use in wrecking or recovering sunken 10 vessels or other objects.

The object of the invention is the provision of apparatus of this character whereby men may descend to relatively great depths in the water and therein perform 15 various operations with certainty and despatch.

The invention consists in the novel construction and combination of devices, as will be hereinafter described and claimed.

20 In the accompanying drawings, Figure 1 is a view partly in vertical section and partly in elevation of devices embodying the present invention. Fig. 2 is a longitudinal vertical section of the diving vessel. Fig. 3 is a horizontal longitudinal sectional view of the front end of the vessel. Fig. 4 is a 25 plan view of the forward end of the grappling devices shown in a rotary position rectangular to that in which it is illustrated in Figs. 2 and 3. Fig. 5 is a vertical sectional view of the rear end of the grappling devices with appliances for operating and regulating the same. Fig. 6 is a sectional view on line 6—6 of Fig. 5. Fig. 7 is a 30 transverse sectional view on line 7—7 of Fig. 2. Fig. 8 is a view partly in end elevation and partly in cross section, said section being taken on line 8—8 of Fig. 3. Fig. 9 is a front elevational view of a door for 35 closing in an emergency the opening in the front wall of the vessel. Fig. 10 is a cross sectional view on line 10—10 of Fig. 5.

The diving vessel proper is constructed with a peripheral shell having a cylindrical 40 rear portion 11, a tapering front portion 12 and rear and forward end walls 13 and 14. Provided in advance of the forward wall 14 is an extension 15 which may be formed with a taper similar to that of the part 12 45 or, as shown, of a cylindrical shape.

16 represents a closure or plate for a man-hole provided in the shell and is desirably formed of a circular plate provided in its periphery with screw-threads to engage 50 screw-threads provided in a frame 17 which

is secured to the shell. As illustrated, the plate is connected at its center by a swivel bolt 18 with an arm 19 which is hingedly connected to an attachment 20 secured to the shell-end 13.

Extending through a stuffing box 21 provided in the forward wall 14 is a tubular shaft 22 disposed axially or nearly so, with respect to the vessel and carrying at its forward end a bifurcated head 23. Provided within the shaft 22 is a rod 24 arranged for longitudinal movement by means of a screw 25 which operates through a screw-threaded hole provided in a cap 26 secured to the rear end of said shaft. The screw is socketed in 60 an axial bore of the rod 24 and is secured against axial movement independently of the rod as by means of keys 27 (Fig. 10) extending through the shaft and engaging in a circumferential groove 25¹ formed in 65 the rod.

28 represents a wheel handle for operating the screw 25. Connected by a pivotal pin 29 to the outer end of the rod 24 is a pair of jaws 30 which extend from between the 70 head branches or cheeks 23¹ to a distance 75 thereinfront.

31 represent spaced rollers mounted upon axles 32 secured to the cheeks 23¹ and serve as roller bearings against which the outer 80 faces of the jaws are pressed through the agency of a sear-spring 33 which tends to open the jaws. When the rod 24 is retracted through the instrumentality of the screw 25, the jaws 30 are drawn into the space between 85 the rollers 31, thereby causing the jaws to close, but when the screw is operated to move the rod forwardly, the jaws are correspondingly advanced and will be opened by 90 means of the spring 33.

The jaws may also be revolvably moved about the axis of the rod 24 by means of a handle or arm 34 of a collar 35 which is secured as by set screws 36 to the shaft 22 so that when the latter is turned the cheeks 23¹ 100 of the head 23 will cause the jaws to be turned therewith.

37 represents a rail supported upon standards 38 and provided with rack-teeth 39, which are engaged by a toothed pinion 40 105 mounted upon a cranked shaft 41 which is journaled in a carriage 42. Said carriage is provided with supporting wheels 43 (Figs. 5 and 6) which operate upon the rail 37 at opposite sides of the rack. Said carriage is 110

connected to the shaft 22 near its rear end so as to serve as a support for the same. As illustrated, the carriage is formed with two branches 44 which are bored to receive the shaft and are spaced to accommodate the collar 35 therebetween.

The carriage 42 is also provided below the wheels 43 with toes 45 which extend below the rail and serve to prevent the uplifting 10 of the carriage when the grappling device approaches the forward end of its travel and to minimize strains to which the grappling device is subjected when the same is bearing a load in its jaws or when protruded to a considerable extent.

Hingedly secured to an attachment 46 provided on the forward wall 14 is a door 47 whose office is to close the opening obtaining within the stuffing box 21 should the grappling devices be ejected as, for example, when such devices would become entangled by rigging or chains of a sunken ship. In such an event, the occupants of the diving vessel would remove the cap 26, the wheel 28, and the set-screws 36, to loosen collar 35. The shaft 22 is then thrust outwardly from the vessel, whereupon the pendent door 47 would be swung to and firmly held by the water-pressure against the stuffing box to prevent the entry of water into the vessel. When unemployed, the free end of the door is supported by a roller 48 thereon tracking upon the shaft 22.

A telescope 49 extends through the wall 14 to give an occupant of the vessel a view of any object which may present itself in front of the vessel. Contributory to this end, I provide a series of electric lamps 50 in the extension 15 arranging them concentrically 40 above and to each side of the axis of the grappling devices. Said lamps are individually inclosed in water-tight tubular receptacles 51 (Fig. 3) secured to socket-connections 52 at their rear ends and having lenses 45 53 which are secured to the outer ends by union nuts 54. To guard said tubes from being damaged I provide an inverted U-shaped casing 55, as best shown in Figs. 3 and 8, which is rigidly secured to the vessel structure and with a space between its lower ends so as to allow articles being drawn into the extension without dragging on the casing below the grappling devices.

Interiorly of the vessel are provided wing 55 compartments 56 for tanks 57 in which are stored a supply of compressed oxygen or an equivalent gaseous or liquid material for rendering the air within the vessel suitable for breathing or to replace the air which 60 may be discharged from the vessel by means of an exhaust pump, as indicated by 58 in Fig. 2.

59 represents a flexible tube connecting the vessel with an air supply pump 60 on an attendant boat or barge B and which may be

utilized when the diving vessel is operating at moderate depths.

The circuit wires for supplying electric current to the lamps provided in the vessel or for the motor 60 to drive the pump 58 70 may be led through the tube 59.

Legs 61 containing heavy material such as lead to serve as ballast elements are detachably connected to the vessel by means of screw-bolts 62 (see Fig. 7) which extend through screw-threaded holes provided in the vessel shell to engage in threaded holes provided in flanges 61¹ formed on the legs. 75

More particularly, a bolt 62 is formed intermediate its length with a peripheral ridge 80 62¹ of sufficient diameter to prevent the same being drawn through a slot of a guard-plate 63, the latter being secured in such position relatively to the shell that the ridge 62¹ will encounter said guard to prevent the withdrawal of the bolt from the threaded hole therefor in the shell and thus obviate any danger of the interior of the vessel being flooded when the ballast members or legs are released when it is deemed 90 expedient to render the vessel flotative. The vessel is also provided with a telephone instrument 64 which is wired to an instrument (not shown) on the barge B for the transmission of instructions as to the manipulation of the vessel from the barge, as 95 will now be explained.

Rigidly secured to the diving vessel and in proximity to the front and rear ends of the cylindrical portion 11 of the vessel, are eye-bolts or attachments 65 for the suspending cables 66 and 67. These cables are directed by guide-sheaves 68 (Fig. 1) to the sheaves of a block 69 and thence extend to power-actuated hoisting drums 70 and 70¹. The 105 sheaves 68 are mounted upon pins 71 which are carried by a beam 72 and positioned near the ends of the same so as to keep the cables spread well apart at the beam. The beam—in turn—is supported at its ends by lines 73 110 from a yoke 74 which is secured to a swivel or eye-bolt 75 which also serves for connecting the block 69 to the end of a boom 76. This boom is connected to the barge-mast 77 for vertical and horizontal swinging movements and which may be regulated by suitable ropes such as 78 and 79 which are handled by the barge crew. Controlling lines, as 80, are furthermore connected with the ends of the beam 72 to enable it to be horizontally rotated when it is desired to correspondingly change the position of the diving vessel and which may be further affected by swinging the boom. When the diving vessel is to be raised or lowered, the drums 70 and 70¹ would be operated in unison to wind up or pay out the respective cables. The diving-vessel, moreover, by a suitable regulation of the appropriate cable, may be regulated to have its forward end inclined either 115 120 125 130

upwardly or downwardly, as may be deemed necessary or desirable to facilitate its operations under water.

The construction and operation of the invention will, it is thought, be understood from the foregoing description. Attention is, however, directed to the provision of suspending means for the diving vessel whereby is afforded a relatively long forward end 5 which may be introduced into an opening in the side of a sunken boat or beneath the same where the space will permit. Furthermore, the grappling devices may be moved outwardly to increase the effective reach or 10 scope of the vessel operations. When the grappling devices are unemployed, the forward ends of the same are housed, as shown in Fig. 3, within the extension 15 for the purpose of protecting the jaws and associated parts from injury. 15

The grappling devices may be used in grasping objects which are to be recovered and also for connecting a hoisting line or the like to a sunken boat as, for example, by 20 engaging a hook provided on such line in a hawse-hole pipe, to a rudder-post, passing the line under the counter of the boat, etc.

Such operations are simplified and may be intelligently performed through the assistance of the telescope and the devices provided to illuminate the field of the telescope. 25

What I claim as my invention, is—

1. In apparatus of the character described, a diving vessel having a cylindrical rear end and a tapering forward portion, 30 cables depending from a boat and respectively connected with the cylindrical portion of the vessel in proximity to the forward and rear ends of such cylindrical portion for sustaining the vessel at predetermined depths and also serving to regulate the longitudinal inclination of the vessel at selected inclinations and grappling devices operable from within the vessel and extending through the forward end of the same. 40

2. In apparatus of the character described, a diving vessel, cables operable from above the water surface for regulating the movements of the vessel when submerged, 45

50 one of said cables being connected to the vessel in proximity to its rear end and the other cable being connected to the vessel at a distance from its front end to afford a relatively long end which projects in front 55 of the adjacent cable to enable such end of the vessel to be introduced within and beneath a sunken boat, said cables also affording means whereby the vessel may be inclined or turned about horizontal and vertical axes. 60

3. In apparatus of the class described, a diving vessel provided with grappling devices extending from one end thereof, and cables operable from above the water surface for regulating the movements of the 65

vessel when submerged, one of said cables being connected to the vessel in proximity to its rear end and the other cable being connected to the vessel at a distance from its front end to afford a relatively long end 70 which projects in front of the adjacent cable to enable such end of the vessel to be introduced within and beneath a sunken boat, said cables also affording means whereby the vessel may be inclined or turned about horizontal and vertical axes. 75

4. In apparatus of the character described, a diving vessel, means operable above the water surface for controlling all of the movements of the vessel when submerged, 80 grappling devices extending through the shell of the vessel and connected with the latter so as to be maintained in approximately parallel relations to the vessel's axis, means provided within the vessel for effecting the rotary and longitudinal movements of said devices with respect to the vessel, means for projecting light in front of said devices, and means whereby the action of the grappling devices may be observed from 85 within the vessel. 90

5. In apparatus of the class described, a diving vessel having a wall at a distance from its forward extremity, devices extending through said wall and adapted to be manipulated from within the vessel, a plurality of lamps provided within the space in front of said wall and inclosed by the peripheral wall of the part of the vessel structure which is in advance of the first named 95 wall and arranged to illuminate the operating end of said devices, and means provided in the first-named wall for observing the operations of said devices. 100

6. In apparatus of the class described, the combination with a diving vessel having a wall adjacent its front end, a stuffing-box provided in said wall, and grappling devices including a shaft which extends through said stuffing-box, of a door hingedly connected to the front side of said wall and adapted to close the opening in said stuffing-box when the grappling devices are removed therefrom. 105

7. In apparatus of the class described, the combination with a diving vessel, and a boat floating at the water surface, of drums provided on said boat, cables extending from the respective drums and connected with said vessel in spaced relation whereby said vessel may be raised or lowered or the horizontal trim thereof may be altered through the instrumentality of said drums, and means operable from the boat for controlling said cables whereby the vessel may be 110 turned about a vertical axis. 120

8. In apparatus of the class described, the combination with a diving vessel provided with grappling devices, and a boat floating at the water surface, of two power-driven 130

drums provided on said boat, cables extending from the respective drums and connected with said vessel in spaced relation whereby said vessel may be raised or lowered or the 5 horizontal trim thereof may be altered through the instrumentality of said drums, and means operable from the boat for controlling said cables whereby the vessel may be turned about a vertical axis.

10. 9. In apparatus of the class described, the combination with a diving vessel and a boat floating at the water surface, of drums provided on said boat, cables extending from the respective drums and connected with 15 said vessel in spaced relation whereby said vessel may be raised or lowered or the horizontal trim thereof may be altered through the instrumentality of said drums, means provided on said boat and acting supplementary to or independently of said drums whereby the elevation of the vessel in the 20 water may be changed, and means operable from the boat for controlling said cables whereby the vessel may be turned about a 25 vertical axis.

10. 10. In apparatus of the class described, the combination with a diving vessel provided with a tapering portion and an extension thereinfront having an open end, of 30 grappling devices projecting through said extension from the interior of the vessel, means for opening and closing the jaws of said grappling devices, and means for advancing or retracting said grappling devices from or into said extension through 35 the open end thereof.

11. In apparatus of the class described, grappling devices comprising a hollow shaft, a bifurcated head provided on the 40 front end of said shaft, rollers carried by said head a rod inclosed by said shaft, a

pair of jaws hingedly connected to said rod and guided by the aforesaid bifurcations, a spring acting to hold said jaws juxtaposed with said rollers, and means engaging the rear end of said rod whereby axial movements may be imparted to the same with respect to the shaft to coöperate with the spring for closing or opening the grappling jaws. 50

12. In apparatus of the class described, grappling devices comprising a hollow shaft, a bifurcated head provided on the front end of said shaft, rollers carried between the bifurcations of said head, a rod 55 inclosed by said shaft, a pair of jaws hingedly connected to said rod and guided by the aforesaid bifurcations, a spring acting to hold said jaws juxtaposed with said rollers, and means engaging the rear end of said 60 rod whereby axial movements may be imparted to the same with respect to the shaft whereby the jaws may be opened or closed through the coöoperative action of said rollers and the spring. 65

13. In apparatus of the class described, a diving vessel having a tapering forward portion, two cables depending from a boat and connected to the vessel for sustaining the same at predetermined depths, said cables being independently operable whereby the longitudinal inclination of the vessel may be regulated, and grappling devices operable from within the vessel and extending through the forward end thereof. 70

Signed at Seattle, Wash., this 28th day of March, 1914.
